United States Patent Office

Des. 189,139
Patented Nov. 1, 1960

189,139

OSCILLOGRAPH

Wayne E. Harrison and Elmer Linna, Tulsa, Okla., as-
signors to Midwestern Instruments, Inc., Tulsa, Okla.,
a corporation of Delaware

Filed Mar. 21, 1960, Ser. No. 59,817

Term of patent 14 years

(Cl. D26—1)

Fig. 2.

Fig. 3.

Fig. 4.

Fig. 1 is a perspective view of an oscilloscope showing my new design;

Fig. 2 is a side elevational view thereof;

Fig. 3 is a front end elevational view thereof; and

Fig. 4 is a rear end elevational view of an oscilloscope. The drawing figures are stippled to indicate contrast in appearance.

We claim:

The ornamental design for an oscilloscope, as shown and described.
